GUN MOUNTING

Lewis Motley, Clapham Common, London,
EnglandApplication February 5, 1938, Serial No. 189,005
In Great Britain February 26, 1937

6 Claims. (Cl. 89—37)

This invention relates to gun mountings, particularly, but not exclusively, for machine guns and automatic rifles.

The object of the invention is the provision of an improved mounting of this character which will be universal, enabling the gun to move freely in any direction while at the same time supporting the weight of the gun in any position, and not impeding either the sight line or the movement of the gunner's body. The gun mounting is thus particularly useful in connection with anti-aircraft work.

A gun mounting in accordance with the invention comprises a rotatable gunner's seat, and a gun-supporting part which swings substantially about the axis of rotation of the gunner's seat and also about another axis transverse to said axis of rotation of the gunner's seat.

In order that the invention may be the more clearly understood a gun mounting in accordance therewith will now be described with reference to the accompanying drawings, wherein:

Figure 1 is a side elevation of said gun mounting.

Figure 2 is an end elevation of the same.

Figure 3 is an end elevation of a portion illustrating a slight modification.

Referring first to Figures 1 and 2 the gunner sits upon a rotatable gunner's seat 1, and the barrel of the gun (not shown) is supported by means of standard fittings 2, 3 carried by a gun mounting which is free, as a whole, to revolve about the vertical axis X—X of the seat as the gunner himself so revolves, so that the muzzle always will be in front of the gunner. The gun mounting itself is also so articulated that the part which supports the barrel is free to rotate both about a vertical axis Y—Y located at the back of the gunner, thereby enabling the gun to swing rapidly in a horizontal direction, and about a horizontal axis Z—Z, also located at the back of the gunner and intersecting the vertical axis Y—Y, whereby the gun is enabled to swing in a vertical direction.

The gunner's seat 1 is rigidly mounted on the top of a spindle 4 which rotates in a main fixed vertical supporting tube 5 which is itself supported by means of legs 6. The supporting tube 5 is provided with bearing elements 7 and 8 at the top and bottom thereof for aligning the spindle 4, and ball bearings 9 are provided as shown between the top of said supporting tube 5 and the bottom surface of a boss 10 welded to the bottom of the gunner's seat. Said boss 10 forms

the means, as shown, by which the gunner's seat is secured to the spindle 4.

For constituting an adjustable friction drag on the rotation of the gunner's seat a nut 11 is screwed on to a stud 12 projecting from the bottom end of the spindle, a friction washer 13 being clamped by said nut against the bottom end of said tube 5 and bearing element 8.

The said fittings 2 and 3 are mounted on a main gun arm 14 whose rear end is bent over at right angles and bears rotatably on a horizontal bearing tube 15, and this horizontal bearing tube is mounted at the upper end of a vertical spindle 16 which extends upwardly from, and rotates in, a vertical bearing tube 17 which is behind, and rigidly secured to, the gunner's seat so as to rotate therewith around the axis X—X. Thus, as stated, the whole mounting rotates about the axis X—X, and the vertical spindle 16 in the vertical bearing tube 17, constitutes the vertical axis of rotation Y—Y of the part supporting the gun, while the bent over end of the gun arm 14 in the horizontal bearing tube 15 constitutes the horizontal axis of rotation Z—Z for said part.

It will be seen that the gun arm 14 passes to the side of the gunner when in the seat 1, whereby said arm and the gun supported thereby are adapted to be immediately manipulated by the gunner, that is, without the intervention of mechanism for that purpose. It is to be understood also that where this expression is found in the claims, it is to be interpreted as meaning that the gunner manually and immediately manipulates the parts referred to without the intervention of operating mechanism.

It will also be seen that the gunner's seat is slightly askew with respect to the axis Y—Y, that is to say, the axis Y—Y is not directly behind the gunner's seat. This has the effect that the recoil tends to turn the gunner's seat towards the gun arm, thereby producing a comfortable pressure between the gun arm and the gunner.

The moment of the weight of the gun and of the main gun arm 14 about the said horizontal axis Z—Z is counterbalanced by means of a spring device. Thus the bent over end of the main gun arm 14 passes completely through the horizontal bearing tube 15 and carries at its extremity a crank 18, and the end of this crank is connected by two heavy tension springs 19 and 20 to a point on a spring supporting sleeve 21 which is rigidly secured to the spindle 16 and depends downwardly over the vertical bearing tube 17. Thus as the gun arm 14 rotates about its vertical axis Y—Y, this spring supporting

sleeve will rotate with it and twisting of the springs 19 and 20 will be avoided. In construction the springs 19 and 20 parallel to one another are connected between two short bars 22 at right angles to them, one of which is centrally pivoted on a short pin 23 extending at right angles from the end of the crank 18 and the other is centrally pivoted on a similar pin 24 extending radially from the spring supporting sleeve 21. Thus the springs can align themselves naturally in response to all possible movements of the gun arm.

It will be appreciated that in proportion as the moment of the weight of the gun and gun arm 14 about the horizontal axis Z—Z increases, the tension of the springs 19 and 20 will increase to counterbalance such increased moment. It will also be seen that the arrangement permits of the gun being swung completely over through the vertical position.

The securement of the spring supporting sleeve 21 to the spindle 16 is effected by means of a clamping ring 25 surrounding the upper end of said sleeve as shown. Said sleeve 21 at its upper end is formed with a vertical slot 26 to render it sufficiently resilient to be clamped on said spindle 16.

Said sleeve 21 also forms the means for determining the vertical position of the spindle 16 in the vertical bearing tube 17, since it is provided with an internal downwardly facing shoulder 27 which rests on the upper edge of said tube 17.

In the example shown, the axis Y—Y is vertical. In some cases it may be preferred to incline this axis to the vertical.

The main gun arm 14 is of variable length, being made, as shown, in two parts 14a and 14b which telescope one within the other. In order 40 to prevent these two parts rotating axially with respect to each other, a pin 28 extending radially from the inner part 14a passes through a longitudinal slot 29 in the outer part 14b. For clamping the two parts 14a and 14b together at any 45 desired adjustment, the rear extremity of said outer part is split to render it resilient, and lugs 30 on either side of the split are adapted to be drawn together or released by means of a simple cam device 31, thereby clamping the outer 50 part to, or releasing it from, the inner part.

As before stated, the fittings 2 and 3 which support the gun are standard fittings. The eyelet at the top of fitting 2 engages with a projection from the barrel of the gun and the fitting 3 engages in a socket in the stock of the gun and locks in said socket by rotating about the axis A.

Any further details are deemed clear from the drawings.

60 In accordance with a somewhat modified arrangement illustrated in Figure 3, the gun barrel may be mounted in a ring 32 which is rotatable in an outer ring 33 whereby the barrel is enabled to rotate on its own axis, and the 65 said outer ring 33 is mounted gimbal fashion whereby the gun is perfectly free to align itself independently of the aforesaid axes X—X, Y—Y and Z—Z. With this arrangement the back fitting 3 is dispensed with, the butt end of the 70 gun being supported by the gunner.

More particularly, the fitting 2 has secured thereto as shown the outer element 34 of a ball race whose inner element consists of the spindle 35 of the outer element 36 of the gimbal mounting, in which outer element the aforesaid

outer ring 33 rotates about its diameter. Ball bearings 37 are also provided between the two rings 32 and 33, the outer ring 33, for this purpose, being made in two parts, viz. an L-section ring and a locking ring which screw into engagement with one another to form a channel section ring receiving the outer edge of the inner ring, with the ball bearings between them. 5

The mounting of the gun is such that the right line comes outside said outer ring 33, and, 10 on occasions, in the clearance between said outer ring and the outer gimbal element 36 which, as shown, is in the form of a half ring.

The projection 38 engages with a corresponding recess in the gun barrel. 15

What I claim and desire to secure by Letters Patent is:

1. A gun mounting, particularly for machine guns and automatic rifles, comprising a part supporting the gun barrel, a basic bearing element, an upright spindle rotatable in said basic bearing element, a second bearing element carried by said upright spindle, in which said part swings about a transverse axis, a crank extending from said part beyond said transverse axis, 20 a sleeve connected to said spindle and extending downwards outside said basic bearing element, and counterbalancing spring means secured at one end to said crank and at the other end to said sleeve. 30

2. A gun mounting, particularly for machine guns and automatic rifles, comprising a part supporting the gun barrel, a basic bearing element, an upright spindle rotatable in said basic bearing element, a second bearing element carried 35 by said upright spindle, in which said part swings about a transverse axis, a crank extending from said part beyond said transverse axis, a sleeve connected to said spindle and extending downwards outside said basic bearing element, said sleeve having an inner shoulder which engages with said basic bearing element to support said spindle in said basic bearing element, and counterbalancing spring means secured at one end to said crank and at the other end to said sleeve. 45

3. A gun mounting particularly for machine guns and automatic rifles, comprising a rotatable gunner's seat, a basic bearing element mounted on said gunner's seat behind the gunner so as to rotate with said seat about the axis of 50 rotation thereof, an upright spindle rotatably supported by said basic bearing element, a second bearing element carried by said upright spindle, a part supporting the gun barrel and rotatably supported by said second bearing element so as to swing about a transverse axis, said part passing from the rear to one side of the gunner, so as to be adapted to be manipulated immediately by the gunner for swinging thereof about both said upright and transverse axes. 60

4. A gun mounting particularly for machine guns and automatic rifles, comprising a rotatable gunner's seat, a basic bearing element mounted on said gunner's seat behind the gunner so as to rotate with said seat about the axis of rotation thereof, an upright spindle rotatably supported by said basic bearing element, a second bearing element carried by said upright spindle, a part supporting the gun barrel and rotatably supported by said second bearing element so as to swing about a transverse axis, said part passing from the rear to one side of the gunner, so as to be adapted to be manipulated immediately by the gunner for swinging thereof about both said upright and transverse axes, a crank 70

extending from said part beyond said transverse axis, and counterbalancing spring means secured at one end to said crank and at the other to said upright spindle.

- 5. A gun mount comprising a base, a gunner's seat including a bottom frame, means mounting said seat and frame on the base to rotate on a vertical axis, said frame having front and rear ends, a gun carrying device laterally displaced from the longitudinal center line of the frame, and means connecting said device to the frame behind the seat and providing horizontal and
- 6. A gun mount comprising a base, a gunner's seat including a frame, means mounting said seat and frame on the base to rotate on a vertical axis, a gun barrel carrying device positioned at one side of the seat, and means connecting said device to the frame behind the seat and providing horizontal and vertical rotational axes for the training and elevation of a gun held by the gun carrying device.

6. A gun mount comprising a base, a gunner's seat including a frame, means mounting said seat and frame on the base to rotate on a vertical axis, a gun barrel carrying device positioned at one side of the seat, and means connecting said device to the frame behind the seat and providing horizontal and vertical rotational axes for training and elevation of the gun.
